UNITED STATES PATENT OFFICE.

FOSTER J. HULL, OF HAGERSTOWN, MARYLAND, ASSIGNOR TO PANGBORN CORPORATION, OF HAGERSTOWN, MARYLAND, A CORPORATION OF MARYLAND.

SAND-BLAST-BARREL LOADING.

Application filed January 22, 1926. Serial No. 83,034.

In cleaning castings by means of the sand blast machine, an important source of expense in the form of labor, and delay resulting in loss of the operating time of the machine, is that incident to handling the castings in loading the machine. The cost of labor for this purpose and the reduction of the productive period of the machine together are in many instances a considerable item.

10 The present invention relates to power-operated loading apparatus whereby the bulk of the expense for hand labor and the loss of time in loading are eliminated. The invention also includes details of the machine 15 whereby it is adapted to the use of the power-loading means, some of which details are of importance independently of the power loading means.

The subject-matter of the invention comprises a loading receptacle referred to in the trade as a skip which is transported in any suitable manner. In the form shown it is suspended from and carried by a travelling crane, being filled from a supply of castings 20 in any convenient position, hoisted and carried by the crane to the machine and brought into a position in which it dumps directly 25 into the barrel of the machine. The apparatus shown includes means for guiding the skip into dumping position, the said guides being preferably on the front of the machine. The guides lead to an abutment which determines the dumping position. In the form 30 shown these members co-operate with fol- 35 lower means as rollers on the skip, the skip being otherwise provided with a locking sus- 40 pension mechanism which supports it in up- 45 right position and by which it is released at the will of the operator when the skip is in dumping position, the release of the sus- 50 pension lock in this position serving to dump the skip.

For the purpose of power filling, the apparatus is provided in addition to the guiding means, etc., with a special door in the machine casing which, while it completely closes and seals the machine casing during operation, opens so as to expose the filling and dumping opening of the barrel at the top 55 of the machine, so that the castings may be dumped from the skip directly into the barrel without handling. The features thus outlined and other features and details contributing to the power-loading operation,

though some of them are capable of being otherwise utilized, and all of them are capable of being widely varied, constitute the subject-matter of the invention.

In the accompanying drawing I have illustrated a sand blast apparatus of the direct pressure rotary barrel type, the same being equipped with a power feed and being constructed and provided with features and details adapting it to the use of the power-feeding operations in accordance with the preferred form of the invention.

In the drawings

Figure 1 is a side view in the nature of an assembly of a sand blast barrel apparatus showing the power feed including loading 70 skip, crane and hoist, and other features of the machine contributing to the power feed.

Figure 2 is a rear elevation of the skip or car, the suspension for the same and the suspension lock which holds the car normally 75 in upright position and prevents dumping until released, the apparatus being locked.

Figure 3 is a similar view of the suspension lock released, the dumping skip or car, etc., being omitted for convenience of illustration. 80

Figure 4 is a side elevation of the dumping skip and suspension, the skip being shown in upright position or position of equilibrium with the suspension locked.

Figure 5 is a perspective view of the skip 85 or car dumped and shown in dumping position.

Figure 6 is a section through the suspension shaft showing one of the locking shives from the inner side.

Figure 7 is a section through the casing on a plane at right angles to the axis of the barrel showing the barrel in side elevation with the casing door and actuating means in elevation. This view is taken in the opposite direction from that of Figure 1. 90

Figure 8 is a front view of the sand blast apparatus, the casing door being shown part in elevation and part removed to illustrate the barrel and barrel door, the door actuating 100 shaft with its parts being shown in section. The bottom of the machine is broken away for convenience of illustration.

Referring to the drawings by numerals, each of which is used to indicate the same or similar parts in the different figures, the apparatus as shown comprises a sand blast barrel apparatus 1, having a rotating barrel 2

enclosed within the casing 3, the barrel being filled or charged by means of a loading car or skip 4 suspended from the hoist 5 of a travelling crane 6 by means of dumping and locking suspension 7.

More particularly in the apparatus as shown the barrel 2 is rotated by any suitable means as gearing 9 to turn the castings and present their different surfaces, and streams 10 of abrasive and air under pressure are injected into the barrel and directed against the exposed surfaces of the castings, the abrasive streams entering at the ends by way of nozzles 8. The castings to be cleaned 15 are introduced into the barrel and removed by way of barrel door opening 10 closed by the barrel door or cover 11.

The barrel being turned to the position illustrated, particularly in Figure 1, with 20 the door opening 10 in the upper forward quadrant, this portion of the barrel is uncovered, so that the castings may be poured or dumped into the barrel from and by the power-operated feed to be described. The 25 barrel door opening is exposed by and through casing door filler opening 12-12 located in the front and front top portion of the casing, and closed to seal the casing and prevent the escape of dust and abrasive 30 by the loading door 14, the same comprising an arcuate plate 15 of somewhat less than 90° hinged to the casing at the top at 16 to swing upwardly in opening, as shown in Figure 1, and downwardly to closed position 35 as shown in Figure 7. The filler door also includes a flat plate 17 having a hinged connection at its upper edge at 18 to and with what is in the closed position the lower edge of the arcuate plate 15. This plate hangs 40 straight downward in closed position, closing the front of the casing below the arcuate plate and from a point just above the horizontal plane of the centre of the barrel to the bottom of the casing. In open position 45 the plates are automatically folded over on each other as shown in Figure 1 giving a large opening at the top and upper portion of the front side with a comparatively short radius of swing. The door is conveniently 50 operated for filling by means of a hand crank and chain gearing, and connections adjacent the front of the machine, as illustrated in Figure 1.

The connections as shown include a 55 sprocket 20 which may be operated by hand crank 21, which sprocket in turn drives a chain 22 which engages and rotates a sprocket 24 and the casing door actuating shaft 25 to which the sprocket is secured. 60 This shaft is mounted in suitable bearings 26 supported well above the casing and to the rear of the door opening on uprights 27 secured at their bases to the casing at 28. The shaft 25 carries deeply grooved shives 29, 65 each operating a chain 30, one end of which

is secured to the shive at the bottom of the groove near the centre of the shive, the other end of the chain being connected to the arcuate member 15 of the filler door which closes the opening in the casing, the chains being, as shown, passed over upright radial supports 31 on the doors and secured at their ends remote from the shives to the edge of the door at 32 which is adjacent the hinge 18 and which edge is the swinging or lower edge in 70 the closed position of the door.

In Figure 8 I have also shown a check or stop chain 33 secured at one end to any fixed point as cross-bar 34, which extends from one upright 27 to the other at the rear, and at its other end to the shaft 25, the winding of the check or stop chain on the shaft serving to limit the operation of the chain gearing and prevent breakage or distortion of the door by drawing it back beyond normal full open 85 position. The stop chain may also serve to stop the operation of the sprockets and chains 30 in the closed position of the door, the stop chain being wound up on the shaft first in one direction, then unwound and wound up in the other direction as the door is operated by means of the gearing 20, etc.

The door may be locked or supported in open position in any suitable manner. In 90 the form of the invention shown this locking is accomplished by means of a pin or bolt 36, which to lock or support the door in open position is inserted in bolt hole 37 in the sprocket casing 38, see Figure 1, the pin being in this way passed through the casing and through one of the open links of the chain 22, thereby locking the parts and preventing all motion of the door-operating mechanism until the pin is removed. The door is locked in open position by the operator, the barrel being likewise stopped in loading position, as shown in Figure 1, just before the skip is brought into operative relation with the front of the machine as hereinafter described.

The loading receptacle or skip 4 with the locking suspension 7 have been referred to herein in a general way. The skip or loading car and suspension are illustrated in Figures 1, 2, 3, 4, 5 and 6. The skip 4, as illustrated, and in the preferred form, though some of the details are not essential, is a scoop-like member having a flat bottom 40, straight sides 41, a rear wall 42 which is inclined upwardly and backwardly, the front end being completely open at 43 for convenience in filling and dumping, and the front edges 44 of the side walls being inclined upwardly and to the rear parallel to the rear wall 42 for convenience in entering the sand blast machine as illustrated in Figure 1 to accomplish the power-loading operation as outlined in the preamble. The loading skip is not only provided with the suspension 7 to be more fully described, by which it is hoisted and carried 110

by means of a travelling crane or other suitable device, but is also provided with two rollers or followers 45, which while they may be referred to as primarily intended to co-operate with abutment 58 and tracks 46 and 47 at the front of the machine in loading, also serve in connection with the single wheel or roller 48 at the rear, to support the skip, so that it may be run on a floor or track.

10 The followers or rollers 45 are in the form of the invention shown mounted on a shaft or axle 50 secured to the bottom of the skip or loading receptacle or car in any suitable manner, as by means of rivets or bolts 51 and bands 52. This axle 50 is of a length sufficient to space the wheels or rollers 45 away from the car as shown, the spacing of the wheels corresponding to the width of the machine casing 1 and incidentally to the spacing of the tracks, etc. 46 and 47 which is practically the width of the machine, the tracks being secured to the sides.

25 The rear wheel 48 is mounted on a suitable bracket 53 secured to the centre of the rear wall, and its only function is to support the rear of the skip when it rests on the floor or other supporting surface. The rear wheel may be pivoted to swing casterwise if desired.

30 The tracks 46 and 47 as shown are secured to the inner surfaces of the front projecting side walls 55 of the casing. These tracks present inwardly projecting surfaces 56 at right angles to the side walls, and they may be in the form of angle irons or any shapes suitable to this purpose.

35 The tracks 46 on each side extend upward vertically from the bottom of the machine, being spaced backward from the front edge of the casing by a sufficient distance to provide side guides as well as supports for contact with the peripheral surfaces of followers or rollers 45, the details not being essential.

40 At a suitable height, which as shown is somewhat below the centre of the barrel, these tracks are curved backwardly toward the barrel, forming an arcuate portion 57 which is nearly 90°, though this curve may be of any form to suit the purpose. This arcuate portion terminates in an upright track 58 which 45 serves as an abutment to stop the forward motion of the skip and to impart a rotary tendency in the direction of dumping. This track may extend upwardly to the top of the side walls. The second track 47 engages 50 the opposite sides of the rollers from that engaged by the track 46 and begins at the upper portion of the casing just above the arcuate portion 57 of the first or inner track. This track 47 as shown and in the preferred 55 form comprises an arcuate portion 59 parallel to the arcuate portion 57 and spaced upwardly and rearwardly therefrom by a distance a little greater than the outside diameter of the rollers or wheels 45. This curved 60 portion 59 terminates in an upright guide

portion 60 of the track 47, the same being spaced from the upright or abutment portion 58 of the track 46 by a distance a little greater than the outside diameter of the rollers 45.

70 The locking suspension 7 in the preferred form as shown, some of the details not being essential, comprises slings 62, one on each side of the skip. These slings consist each of a short chain. Each of these chains is 75 secured at each end by suitable clamping means 63, 64 to two respective fixed points on the corresponding sides of the skip, the point 63 being spaced from the front and the point 64 being near the rear of the skip, the arrangement being preferably such that the skip when loaded has a slight tendency to tip forward, which tendency is restrained by the lock to be described.

80 The slings 62 co-operate each with one of the shives 66 over which they are passed. There is one of these shives on each end of an axle 67 which is carried in the suspension body 68. This member 68 is provided with eyes 69 near its respective ends connected in 85 the form of the invention shown by chains 70 to a ring 71 adapted to be engaged by a hook 72 on the cable of the hoisting element 5 of the travelling crane 6.

90 The suspension body 68 carries at each side 95 of its centre a bolt 73 which slides in the direction of the length of the axle, each bolt being mounted in a suitable guide 74, one near each end of the body, the sliding bolts being actuated togglewise by a swinging arm 100 100 pivoted at its centre by means of a pin 105 105 110 115 120 125 130 135 140 145 150 155 160 165 170 175 180 185 190 195 nature of an enlargement of the groove, the socket being adapted to receive and position the ball, or other positioning member, holding the skip in upright or loaded position, substantially as illustrated in Figure 4, the balls and sockets being correspondingly located for this purpose. The bolts are actuated by means of a controller arm 87 extending outwardly to the operator's side of the machine, 10 i. e., to the left of the operator in facing the machine from the filling side. This transverse arm 87 may be secured to the swinging or the toggle arm 75 intermediately thereof and preferably at right angles thereto as 15 shown. The controller arm 87 is also shown as extending to the right beyond the toggle arm 75 and carrying a counter-weight 88 which tends to normally hold the parts in locked position, the shives being unlocked and the 20 bolts released by a downward pull on the left-hand end of the arm 87 to which a chain 89, see Figure 2, is connected for convenience of the operator. A pull on the chain serves to swing the actuating arm 87 and release the 25 bolts, permitting the skip if unbalanced to dump as illustrated in Figure 1.

In the operation of the machine, the cleaning of a charge or load of castings having been completed and the castings dumped, the 30 casing door 14 is opened, as shown in Figure 1, by rotating the hand crank 21 and actuating the chain gearing, rolling up the chains 30 on the shives 29, and swinging the door to the position shown in Figure 1, where it is 35 stopped by the stop chain 33, and locked by inserting the pin 36 in the hole 37 in the gear casing 38, the pin being thus passed through one of the open links of the chain and held in fixed position in the casing, whereby the 40 chain and door are held as shown in Figure 1. The barrel is then rotated to the position shown, in which the barrel opening 10 is disposed toward the casing door opening 12 so as to be in convenient alignment therewith 45 for the purposes stated.

The skip or loading car 4 is then filled with castings to be cleaned or other articles to be treated by the sand blast. The skip may be filled by scooping or shovelling or by 50 means of a chute. The skip is then hoisted in any suitable manner as by means of travelling crane 5, 6 and carried in suspension to the sand blast machine, or it may be handled by any available means.

55 For the purposes of loading, the skip is caused to approach the front of the machine, the rollers or followers 45 being brought into contact with the inside vertical tracks 46 below the outer track 47, each roller 45 being engaged with one of the tracks, the skip being in the centre of the front of the machine with the open or forward end 43 toward the barrel. To keep the wheels in contact, the hoist of the crane is preferably held a bit in advance 60 of the centre of the skip in the direction of

the centre of the barrel. The skip is then hoisted and the rollers 45 move upward along track 46 and then traverse the arcuate portion 57 and contact abutment 58, both tracks performing a guiding function. The skip is thus guided to the location in which it is shown in Figure 1, the hoist of the crane being still kept a little forward in the direction of the centre of the barrel. The skip is held in upright position throughout the traverse 75 and to the stage of the loading operation just described by the engagement of the balls 85 with the sockets 86 in the shives 66 which are locked by the latch 75.

The skip having been thus guided by the so tracks to a position with its forward end or nose 43 in or over the opening 10 in the barrel, and rollers 45 engaging abutment 58 with the hoist preferably drawing the suspension slightly forward, the operator releases the latch 75, withdrawing the bolts 73 from the keeper notches 80 by throwing the lever 87, which on account of the height of this lever above the floor, may be provided with a pull chain 89 by which the lever is 90 most conveniently engaged for this purpose by the operator.

The latch having been released, the skip being on account of the engagement of the rollers with the abutments 58 and being otherwise on account of the position of the slings 62 and the shives 66, unbalanced, and having a tendency to rock forward to the position shown in Figure 1, swings forward to dumping position as shown, and the castings are 100 dropped by gravity into the barrel. The operator then eases the hoist, unwinding a few inches of cable, and the rollers 45 being partially supported on the portion 57 of the track in the position shown in Figure 1, the 105 skip rocks back to the upright position or the position of equilibrium shown in Figure 4, and the balls 85 roll back into the sockets 86, and the actuating lever 87 being counter-balanced by the weight 88 as described, the bolts 110 73 are returned to the keeper notches 80 which are thus brought in alignment with the bolts, and the skip or car being again locked in equilibrium, may be returned to the point of supply of castings or other materials being 115 treated for the purpose of refilling.

I have thus described specifically and in detail a sand blast barrel apparatus equipped with the power loading appliance of my invention, and the features and details contributing to the operation of the loading apparatus, in order that the nature and method of application of the invention may be clearly understood; however, the specific terms herein are used descriptively rather than in a 120 limiting sense, the scope of the invention being defined in the claims.

What I claim and desire to secure by Letters Patent is:

1. In a sand blast barrel apparatus a bar- 125

rel, a casing having a door opening exposing an upper portion of the barrel, a door covering said opening, the casing having an abutment adjacent the door opening, a dumping skip for filling the barrel, the dumping skip having means co-operating with the abutment, means for suspending the skip in unbalanced condition and bringing it into engagement with the abutment, the suspension means comprising a lock to hold the skip in non-dumping position, and means for throwing the lock whereby the skip is dumped through the opening into the barrel which is provided with a filling opening which may be brought into registration with the casing door opening for this purpose.

2. A sand blast machine having a rotary barrel, a casing enclosing the barrel, the barrel having a filling opening in the side with means for closing the same, and the casing having a door and door opening exposing an upper quadrant of the barrel, the casing door comprising an arcuate plate hinged to the casing at the top, and a second depending plate hinged to the swinging end of the arcuate plate.

3. A sand blast machine having a rotary barrel, a casing enclosing the barrel, the barrel having a filling opening in the side with means for closing the same, and the casing having a door and door opening exposing an upper quadrant of the barrel, the casing door comprising an arcuate plate hinged to the casing at the top, and a second depending plate hinged to the swinging end of the arcuate plate, which latter swings upwardly in opening so that the two plates are in effect folded toward each other, the swing of the door being thereby reduced as compared to the length of the opening exposed.

4. In a sand blast barrel apparatus, a casing having a door opening exposing the entire front half of the barrel, the door for said opening comprising an arcuate plate hinged to the casing at the top rear of the door opening, and a depending plate hinged to the swinging end of the arcuate plate.

5. In a sand blast barrel apparatus, a casing having a door opening exposing an upper portion of the barrel, the door for said opening comprising a plate hinged to the casing, a depending plate hinged to the swinging end of the first plate, and manually actuated gear-

ing for swinging the first plate upwardly about its hinged edge.

6. In a sand blast barrel apparatus, a casing having a door opening exposing an upper portion of the barrel, the door for said opening comprising an arcuate plate hinged to the casing, a depending plate hinged to the swinging end of the arcuate plate, and manually actuated gearing for swinging the arcuate plate upwardly about its hinged edge, and means for locking the gearing to hold the door in open position.

7. In a sand blast barrel apparatus, a casing having a door opening exposing an upper portion of the barrel, the door for said opening comprising a plate hinged to the casing, a depending plate hinged to the swinging end of the first plate, manually actuated gearing for swinging the first plate upwardly about its hinged edge, and a stop limiting the operation of the gearing.

8. In a sand blast barrel apparatus, a casing having a door opening exposing the barrel, the door for said opening comprising a plate hinged to the casing at the top rear of the door opening, a depending plate hinged to the swinging end of the hinged plate, and manually actuated chain gearing for swinging the hinged plate upwardly about its hinged edge, means for locking the gearing to hold the door in open position, and a stop chain limiting the operation of the chain gearing and determining the scope of operation of the chain gearing to prevent straining of the door.

9. A sand blast barrel apparatus, a casing having a door opening over the top of the barrel and in front of the barrel, a door for closing the opening comprising a plate pivoted at the upper rearward edge of the opening, and means for swinging said plate comprising a rotary shaft with a shive, a chain connected to the shive to be wound up thereon, chain gearing for rotating the shaft, manually actuated means for operating the chain gearing, and a second chain connected to the shaft to be wound up as the door is opened, the chain being also connected to a fixed point to act as a stop to limit the movement of the door in opening.

Signed by me at Hagerstown, Maryland, this 20th day of January, 1926.

FOSTER J. HULL.
